UNITED STATES PATENT OFFICE.

GEORGE S. JOHNSTON, OF EVANSTON, ILLINOIS, ASSIGNOR TO GEO. S. JOHNSTON COMPANY, OF CHICAGO, ILLINOIS, A CORPORATION OF ILLINOIS.

GOGGLES.

1,392,832.

Specification of Letters Patent.

Patented Oct. 4, 1921.

Application filed September 15, 1919. Serial No. 323,990.

To all whom it may concern:

Be it known that I, GEORGE S. JOHNSTON, a citizen of the United States, residing at Evanston, in the county of Cook and State 5 of Illinois, have invented certain new and useful Improvements in Goggles, of which the following is a specification.

This invention relates generally to goggles that may be applied to various uses; more 10 particularly it is concerned with a novel and improved form of goggle frame and guard associated therewith which is of strong and simple construction, and permits of the glasses or lenses being readily withdrawn or 15 replaced as required.

The features of this invention are susceptible of embodiment in a number of different forms, a few of which are suggested 20 in the drawings. Accordingly, the objects and purposes of this invention may best be understood from the specification to follow wherein reference is made to the accompanying drawings which exhibit the invention in four different constructions, in the following 25 manner:

Figure 1 is a plan view of one form of the goggle;

Fig. 2 is a front elevation thereof;

Fig. 3 is a longitudinal section taken on 30 line 3—3 of Fig. 1;

Fig. 4 exhibits one goggle eye or bow with its associated parts removed;

Fig. 5 is a transverse section taken on line 5—5 of Fig. 1; and

Figs. 6 to 10 inclusive, are similar views 35 respectively, of another form of goggle.

The frames and guards of the devices that will now be described in detail are preferably constructed of some light, strong, and 40 suitable material, such, for instance, as fiber, or any serviceable composition that possesses the properties requisite for this invention.

Figs. 1 to 5 inclusive.—A frame is employed consisting of two parts each in the 45 form of an eye or bow 21 having a bridge piece 22 that is adapted to coöperate with the other when resting upon the nose. The two parts of the frame are shown to be flexibly connected as by means of a strap 23.

50 Each eye presents an opening which is sub-

stantially circular except for the provision of one or more projections 24 and a leaf spring 25 all as best shown in Fig. 4. As a convenient means of securing the leaf spring in place, I have shown it to be attached to a 55 U-shaped frame 26 that fastens to the bow, the spring normally acting to project into the circular area within the bow, but having rearwardly thereof a recess 27 into which it may recede under pressure. The construction of the two eyes is identical, so that the same reference numerals have been applied to the corresponding parts of each.

The mounting of the glasses or lenses in this goggle is so arranged and constructed 60 as to permit them to be readily attached or detached relative thereto and to hold them immovably in place thereon. For this purpose I employ a guard 28 of suitable shape and form to properly exclude light and particles, and provided with a cylindrical portion designated as 29 whose external diameter is slightly reduced at its outer end 30, an annular shoulder 31 being thereby provided, as shown. Through the wall of the guard in 65 the thinned portion 30 immediately adjacent the shoulder 31, an elongated opening 32 is provided extending for slightly less than 180 degrees so as to provide a means of entry or withdrawal for a glass or lens 33 which is 70 adapted to be seated within a channel 34 provided interiorly of the eye in a portion thereof not occupied by the opening 32. The relation of the channel 34 and opening 32 are best shown in Fig. 3. Other shorter 75 openings 35 are also arranged to register with the projections 24, the thickness of the wall 30 adjacent such openings as at 36 being still further reduced for a reason that will presently appear. Each guard is equipped 80 with a suitable cord or strap adapted to connect with the other when passed around the head so as to hold the goggle in place, this being suggested merely as a convenient means for this purpose.

In assembling the glasses or lenses into the present goggle, the guards are first removed so as to allow the glasses to be slipped into place through the openings 32. Each guard is then inserted within its eye 21 and this is 95 100

accomplished by a sliding movement accompanied by a forced recession of the spring 25. During this operation, the two projections 24 are required to slide over the thinned portions 36 preparatory to lodging within the openings 35. These projections which connect the guard to the eye at two points are supplemented by the action of the spring 25 which projects through the opening 32 into 10 direct contact with the edge of the lens, the effect being not only to hold the guard securely in place, but also to exert at all times a pressure upon the lens tending to prevent any movement thereof within the guard. It 15 is obvious that a withdrawal of the lens from the guard may be effected by a reversal of the operations described.

Figs. 6 to 10 inclusive.—A frame is employed consisting of two parts each in the 20 form of an eye or bow 41 having a bridge piece 42 that is adapted to coöperate with the other when resting upon the nose. The two parts of the frame are shown to be 25 flexibly connected as by means of a strap 43. Each eye presents an opening which is substantially circular except for the provision of one or more projections 44, one of which, designated as 45, is, according to this 30 invention, carried upon a resilient arm 46 integral with the frame, and adapted under pressure to recede into a slot or opening 47. Normally the arm 46 remains in circular alinement with the eye 41 so as to maintain its projection 45 inwardly of its inner 35 periphery. The construction of the two eyes is identical so that the same reference numerals have been applied to the corresponding parts of each.

The mounting of the glasses or lenses in 40 this goggle is so arranged and constructed as to permit them to be readily attached or detached relative thereto, and to hold them immovably in place thereon. For this purpose I employ a guard 48 of suitable shape 45 and form to properly exclude light and particles, and provided with a cylindrical portion designated as 49 whose external diameter is slightly reduced at its outer end 50, an annular shoulder 51 being thereby 50 provided, as shown. Through the wall of the guard in the thinned portion 50 immediately adjacent the shoulder 51 an elongated opening 52 is provided extending for slightly less than 180 degrees, so as to provide 55 a means of entry or withdrawal for a glass or lens 53 which is adapted to be seated within a channel 54 provided interiorly of the eye in a portion thereof not occupied by the opening 52. The relation of the channel 60 54 and opening 52 are best shown in Fig. 8. Other shorter openings 55 are also arranged to register with the projections 44, the thickness of the wall 50 adjacent such openings, as at 56, being still further reduced 65 for a reason that will presently ap-

pear. Each guard may be equipped with a suitable cord or strap adapted to connect with the other when passed around the head so as to hold the goggle in place, this being suggested merely as a convenient means for 70 this purpose.

In assembling the glasses or lenses into the present goggle, the guards are first removed so as to allow the lenses to be slipped into place through the openings 52. Each guard is then inserted within its eye 41 and this is accomplished by a sliding movement accompanied by a forced recession of the resilient arm 46 upon which is carried the projection 45. During this operation the projection 44 is required to slide over the thin portion 56 80 preparatory to lodging within one of the openings 55, so that it may be snapped into place within this opening. This projection 44 which connects the guard to the eye at one point is supplemented by the other projection 45 which springs into another opening 52 where it directly contacts with the edge of the lens, the effect being not only to hold the guard securely in place, but also to exert at all times a pressure upon the lens tending to prevent any movement thereof within the guard. It is obvious that a withdrawal of the lens from the guard may be effected by a reversal of the operations described.

The several forms of goggle that have now been explained in detail are all simple in their construction, and render facile a substitution of glasses whenever this may be desired. In 100 addition these constructions securely hold the glasses in place, and prevent leaks therearound. Obviously my invention is susceptible of embodiment in other forms than the ones herein suggested, and in respect of any 105 changes or modifications that may utilize the principle of this invention, as described in the claims below, I desire that they should be included within the scope of this patent.

I claim:

1. A goggle comprising a frame formed to provide two eyes each having a slotted bridge portion protruding from one side thereof, the frame of the eye being severed at one portion adjacent the bridge to provide an arm having capacity for receding into the slot, the arm carrying on its movable extremity an element normally projecting into the eye, a second projection in another portion of the eye, a guard for each eye having a cylindrical portion adapted for insertion therein, and a glass mounted within the guard, the guard walls having openings into which the fixed and movable projections may enter, the latter being required to recede toward the slot as a condition precedent to the insertion of the guard into the eye, substantially as described.

2. A goggle comprising a frame formed to provide two eyes, each having a slotted

bridge portion protruding from one side thereof the eye wall adjacent the bridge being formed to recede under pressure into the slot and carrying thereon an element which 5 normally projects into the eye, a guard for each eye having a cylindrical portion adapted for insertion therein, and having means

with which the element projecting from the arm may engage to lock the guard in place, substantially as described.

GEORGE S. JOHNSTON.
